Primary Examiner—A. Hugo Word*Attorney, Agent, or Firm*—Marshall, O'Toole, Gerstein,
Murray & Borun[57] **CLAIM**

The ornamental design for a brush handle, as shown and
described.

DESCRIPTION

FIG. 1 is a top, front, and left-side perspective view of a
brush handle showing the new design;

FIG. 2 is an elevational view of one side thereof, the other
side being a mirror image thereof;

FIG. 3 is a front view of the brush handle; and,

FIG. 4 is a top plan view thereof.

The rear of the brush handle is unornamented and follows
the contour that is shown to the right of FIGS. 1, 2, and 4.
